UNITED STATES PATENT OFFICE.

WILLIAM R. OYLER, OF TOPEKA, KANSAS.

POST-EXTRACTOR.

SPECIFICATION forming part of Letters Patent No. 376,903, dated January 24, 1888.

Application filed August 25, 1886. Renewed June 11, 1887. Serial No. 241,026. (No model.)

To all whom it may concern:

Be it known that I, WILLIAM R. OYLER, a citizen of the United States, residing at Topeka, in the county of Shawnee and State of Kansas, 5 have invented certain new and useful Improvements in Post-Lifters, of which the following is a specification, reference being had therein to the accompanying drawings.

Figure 1 is a perspective of the device ready 10 to be operated. Fig. 2 is a side elevation of the lever. Fig. 3 is a top plan of the block. Fig. 4 is an edge view of the toothed part of the lever. Fig. 5 is a front elevation of the block. Fig. 6 is a perspective view of the block. 15 This device belongs to that class called "post-lifters" or "stump-extractors," and the novelty consists in the construction and combination of the several parts—namely, the base-block and the independent and detachable lever and toothed blade, whereby the said lever 20 is fulcrumed on the block and the blade operated in said slot, so as to have an upward lifting force on the post or other thing to be lifted, all as will now be more fully set out and 25 explained, reference being had to the accompanying drawings.

In the drawings, A denotes the fulcrum block or base, which may be made of wood and in several pieces or of metal cast in one piece. If 30 made of wood, I prefer to have the grain of the bottom piece at right angles to that of the upper piece. In the front part is a vertical and somewhat tapering slot, a, about three-fourths of an inch wide and extending back a third (more 35 or less) of the length of the block. The upper ends of the sides a', forming this slot, are beveled at a².

Integral with the block or securely fastened 40 on each side of the slot a, on the tops of the side a', are the crotches B, one on each side, made generally in the form of an inverted W. The front ends of this, when the block A is made of wood, fit snugly on its beveled ends a²; but when the block is cast these 45 crotches will be an integral part thereof. In the rounded parts b of the crotches the rounded ends c of the split lever Crest, and are capable of being freely moved thereon. The blade D of the lever, which is rigidly secured at one 50 end between the split ends c of the lever, is adapted in shape and size to move freely be-

tween the crotches and in the slot a in the block A. The front or edge part of the lever-blade is curved, so that in operation it shall act as an eccentric, and provided with teeth 55 d, generally V-shaped. As thus made it will be observed that the lever and blade practically form one piece, and are readily detachable from the base-block when necessary; but, if desired, the lever could be permanently secured to and upon the block. When the blade is in position for use, the points of these teeth extend upwardly and somewhat outwardly. The teeth are also staggered. Thus said teeth will hold to a wide surface when fixed in a 60 railroad-tie, post, or other object being lifted, so that, if the wood of the said tie or other article is not wholly firm, as by rot or otherwise, the edge of the blade will yet be able to get a secure and unslipping hold. As a matter of fact, by means of this device thus constructed, with its block and lever actuated blade, I have been able to lift at the first trial 65 any wooden post, telegraph-pole, or railroad-tie, no matter whether sound or partially decayed, from the ground.

If desired, the blade and lever can be made in one piece.

To operate said machine, I place the slotted end of said fulcrum-block against the post, 80 railroad-tie, or other object to be lifted, said iron crotches or bearings thereon being up. Then I place said lever with said blade curved and so made an eccentric, and toothed, as aforesaid, in the said rounded crotches or bearings on said fulcrum-block. Then I bear down on said lever by the handle thereof. Said teeth engage with and sink into considerable width of the post, tie, or other object to be raised. As a post is raised and becomes loose, said 90 toothed semicircle of iron does not let go, being an eccentric, and pressing more and more against it as it is raised; nor does it let go because the wood may be decayed, said teeth being staggered and engaging with such object on different lines.

Having thus described my invention, what I consider new, and desire to secure by Letters Patent, is—

1. A post-lifter or similar device consisting 100 of a base or fulcrum block vertically slotted in front and having crotches or lever-seats on

- each side of said slot, combined with a lever having at its lower end a blade fitting into said slot and having staggered teeth, substantially as described.
5. 2. The fulcrum-block slotted in front and having the crotches at the top and on each side of the said slot, combined with the lever having rounded ends to rest on the said crotches and the blade provided with staggered teeth on its curved front edge, substantially as described.
3. The combination of the block A, slotted vertically in front at *a* and having crotches B,

one on each side of said slot, and combined with a lever, C, and blade D, having teeth *d* on its eccentric edge, substantially as described.

4. A base-block having a slotted end, combined with a detachable lever having the toothed blade, fulcrumed on said block, substantially as described.

In testimony whereof I affix my signature in presence of two witnesses.

WILLIAM R. OYLER.
